UNITED STATES PATENT OFFICE

HANS HAUGEN, OF FARGO, NORTH DAKOTA

COLLAPSIBLE BOAT

Application filed July 30, 1928. Serial No. 296,241.

This invention relates to boats, an object being to provide a non-capsizable, non-sinkable boat which is especially adapted for hunting.

Another object of the invention is the provision of a boat of this character which may be knocked down or collapsed for storage or shipment, and when set up for use will provide a light shallow draft boat which is easily 10 propelled and handled and is staunch and seaworthy in rough weather.

With the above and other objects in view, the invention further includes the following novel features and details of construction, to 15 be hereinafter more fully described, illustrated in the accompanying drawings and pointed out in the appended claims.

In the drawings:—

Figure 1 is a plan view of a boat constructed 20 in accordance with the invention and set up for use.

Figure 2 is a side view of the same.

Figure 3 is an enlarged fragmentary section on the line 3—3 of Figure 2.

25 Figures 4, 5 and 6 are enlarged sections taken respectively on the lines 4—4, 5—5, and 6—6 of Figure 1.

Figure 7 is a plan view on an enlarged scale showing the main section of the boat.

30 Figure 8 is a fragmentary edge view showing the manner of mounting the oar lock bracket.

Figure 9 is a section on the line 9—9 of Figure 8.

35 Figure 10 is a plan view showing a fragmentary portion of the boat with the bracket in place.

Referring to the drawings in detail where- 40 in like characters of reference denote cor- responding parts, the boat is formed of a plurality of separate sections or units, the main section being indicated at 10. This sec- 45 tion is provided with side walls 11 which are shown as parallel, and with end walls 12, this section defining a cock pit 13 which may be provided with a false bottom 14. The side walls 11 and end walls 12 are provided with outwardly extending horizontal flanges 14, 50 the walls 11 and 12 forming a combing around

the cock pit which is surmounted by the flanges 14.

The boat further includes end sections 15 which are removably attached to opposite ends of the main section and are preferably 55 tapered as shown.

Side sections 16 are also provided for removable attachment to opposite sides of the main section and these side sections and the end sections 15 are hollow and air tight so as to 60 provide buoyant pontoons which support the main section and prevent sinking. In addition, by extending the side sections 16 outward from opposite sides of the main section, sufficient beam is provided to prevent cap- 65 sizing.

In order to removably secure the sections 15 and 16 to the section 10, the latter is pro- 70 vided at each end upon opposite sides with plates 17. These plates have spaced eyes 18 along their opposite edges and these eyes are adapted to be registered with spaced eyes 19 which are carried by plates 20 at oppo- 75 site sides of each end section 15. Other eyes 18 of the plates 17 are adapted to register with eyes 21 which are carried by plates 22 at opposite ends of the side sections 16, while pins 23 which are removably held in the eyes 80 act to secure the sections 15 and 16 to the main section.

Braces 24 which have their forward ends secured to the outer ends of the sections 15 and their rear ends secured to the flanges 14 at opposite ends of the main section, act 85 to brace and stabilize the outer ends of the end sections.

By reference to Figure 1 of the drawings it will be seen that when the boat is set up for use, its opposite sides taper from amidships in an unbroken line to the opposite ends of the boat so as to provide an easily handled craft which is especially adapted for use in shallow water. The boat is intended to carry two men, although it may be made in different sizes and have a different 90 carrying capacity. The sections 15 and 16 will have sufficient buoyancy to maintain the carrying capacity of the boat even when the main section is filled with water. The boat will also support its carrying capacity 95 100.

even when turned bottom up. If desired, the side sections 16 may be dispensed with and the boat used with only the sections 15. When not in use, the sections 15 and 16 may be stored within the main section 10 as indicated in Figure 7 of the drawings. In this figure, the sections 15 and 16 are positioned within the main section beneath the false bottom, one section of the latter being omitted.

10 The invention further provides oar lock brackets which are adjustable upon opposite sides of the main section, the side walls of the latter extending above the top of the side sections as shown in Figures 4 of the drawings. Each of these oar lock brackets comprises an upwardly extending member 25 which is provided with openings 26 to receive the oar lock. Extending from the bottom member 25 in opposite directions are arms 27 which carry at their outer ends downwardly extending lugs 28. These lugs are slidable upon opposite sides of the flanges 14 so that the brackets may be adjustably positioned. Substantially U-shaped clamps 29 extend 25 from the arms 27 and beneath the flanges 14 to hold the brackets in place, while clamping screws 30 serve to clamp the brackets in adjusted position.

30 The invention is susceptible of various changes in its form, proportions and minor details of construction and the right is herein reserved to make such changes as properly fall within the scope of the appended claims.

Having described the invention what is 35 claimed is:

1. A collapsible boat comprising a main section, hollow buoyant end sections, hollow buoyant side sections, said end and side sections being adapted to be positioned within 40 the main section when the boat is not in use, and means at the corners of the main section and common to the end and side sections to removably secure the end and side sections to the ends and sides of the main section 45 upon the outside of the latter.

2. A collapsible boat comprising a main section, hollow buoyant end sections, hollow buoyant side sections, said end and side sections being adapted to be positioned within 50 the main section when the boat is not in use, and means to removably secure the end and side sections to the ends and sides of the main section upon the outside of the latter, and braces having their outer ends secured to 55 the outer ends of the end sections and their inner ends secured to the main section.

3. A collapsible boat comprising a main section including side walls and end walls and defining a cock pit, tapered buoyant end 60 sections extending from opposite ends of the main section, outwardly curved buoyant side sections at opposite sides of the main section, attaching plates upon opposite sides at each end of the main section, attaching plates 65 at each end of the side section, attaching

plates at opposite sides of the inner ends of the end sections, and means providing a detachable connection between the plates to removably secure the side and end sections to the main section.

70 In testimony whereof I affix my signature.
HANS HAUGEN.
